DESIGN FOR A COASTING SLED

Frederick A. Richards, Oakland, Calif.

Application April 13, 1934, Serial No. 51,401

Term of patent 14 years

To all whom it may concern:

Be it known that I, FREDERICK A. RICHARDS, a citizen of the United States, and a resident of Oakland, in the county of Alameda and State of California, have invented a new, original, and ornamental Design for a Coasting Sled, of which the following is a specification, reference being had to the accompanying drawing, forming part thereof, wherein

Figure 1 is a perspective elevation of a coasting sled embodying my new design.

Figure 2 is a front elevation of the coasting sled.

Figure 3 is a side elevation of the coasting sled.

I claim:

The ornamental design for a coasting sled substantially as shown.

FREDERICK A. RICHARDS.
